UNITED STATES PATENT OFFICE.

FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,212,203.

Specification of Letters Patent.

Patented Jan. 16, 1917.

Application filed August 7, 1911. Serial No. 842,766.

To all whom it may concern:

Be it known that I, FREDERICK M. FURBER, a citizen of the United States, residing at Revere, in the county of Suffolk and

5 State of Massachusetts, have invented certain Improvements in Machines for Use in the Manufacture of Boots and Shoes, of which the following description, in connection with the accompanying drawings, is a 10 specification, like reference characters on the drawings indicating like parts in the several figures.

The heels of shoes are ordinarily attached by nails which are driven from the outside 15 and clenched in the interior of the shoe. There is thus formed in the interior of the shoe in that portion which supports the heel of the wearer,—said portion being hereinafter referred to as the heel-seat of the shoe,— 20 an uneven surface caused by the clenched ends of the attaching nails. In order to cover the ends of these nails it is customary to apply to the heel-seat a piece of material of suitable shape coated on the under side 25 with cement, said piece being hereinafter referred to as the lining-piece or heel-seat lining. Hitherto this work has been performed manually, and the general object of the present invention is to provide a machine 30 for accomplishing it in whole or in part.

Accordingly one feature of the invention comprises in a machine of the class described a support over the end of which a 35 shoe may be positioned to receive lining material, means for feeding said material relatively to said support into position to contact with the inside of the bottom of a shoe placed upon said support, and means for 40 coating said material with an adhesive substance prior to its application to the inside of said shoe.

Another feature of the present invention consists in the provision of mechanism for 45 applying a lining-piece to a shoe, and means for actuating said applying mechanism; and in the machine herein illustrated and described this means is automatic and becomes operative upon presentation of a shoe. This 50 lining-piece, as has been stated, is usually fastened to the heel-seat by means of cement; and another feature of the invention consists in the provision in a machine for ap-

plying such a lining-piece to a shoe of mechanism for applying cement to the lining- 55 piece and means for actuating said mechanism.

Another feature of the invention consists in the provision in a machine of the class described of mechanism for cutting from suitable material a lining-piece for a shoe and means for actuating said cutting mechanism; and in the illustrative machine the material is supplied to the machine in the form of a strip which is intermittently fed 60 forward by automatic feeding mechanism.

In the illustrative embodiment of the invention there is shown a machine having mechanism for feeding forward a strip of fabric or other material, mechanism for applying cement to said strip, mechanism for cutting a lining-piece from said strip, and mechanism for applying said lining-piece to the heel-seat of a shoe. Inasmuch, however, as these operations have hitherto been carried out separately and by hand it will be understood not only that these mechanisms might be employed singly to advantage but that certain combinations of them may be used without using them all. 75

Accordingly, other features of the invention consist in such combinations of these mechanisms and constructional details of their parts as will be described in connection with the illustrative machine and pointed 80 out in the appended claims.

Referring to the accompanying drawings:

Figure 1 is a side elevation of the machine in which the present invention is embodied, the lower portion of the machine being shown in section on line 1—1 of Fig. 2; Fig. 2 is a rear elevation of the machine with certain parts shown in section; and Fig. 3 is a rear elevation on a larger scale of certain portions of the strip-feeding and cement applying mechanisms. 90

Mounted in a bearing in the frame 1 is the stem 2 of a turret 3 which may be held in any desired angular position by means of 10 a spring-pin 5 which may be manipulated by a handle 7. This turret carries a plurality of shoe receivers 9 of different size, and each receiver carries at its inner end a die 11 which is designed to cut out a lining- 10 piece of proper shape. These dies, when in

the position of the upper one shown in Fig. 1, are adapted to coöperate with a hollow cutting block 13 to cut the lining-piece from a strip 15 of suitable material. The stem 2 of the turret 3 is provided with a reduced portion 17, and the bearing which sustains it is counterbored to provide a proper seat for a spring 19 which bears with one end against the shoulder formed by the reduced portion 17 and with the other against the bottom of the counterbore so that the turret is normally held outwardly as shown in Fig. 1, this outward movement, due to the spring, being limited by a washer 28 and a nut 20 which latter is threaded on the extreme end of the stem 2.

Rotatably mounted upon a stud 21 are three levers, a clutch-actuating lever 23, a feed-actuating lever 25, which serves also to actuate the applying mechanism, and a die-actuating lever 27. The clutch-actuating lever 23 engages with its upper end the end of the stem 2 and with its lower end the pawl 26 which controls the clutch by which the continuously rotating driving pulley 29 is caused to engage the driving shaft 31. The clutch made use of is similar to that shown in the patent to James Horton, No. 260,394, and will not be described in detail since any suitable one-revolution clutch may be made use of, if desired. This driving shaft is provided with a double crank 37; and the sleeve 115, which is fast to the shaft, is provided with a cam 41. The crank 37 through the link 39 operates the lever 25, and the cam 41 operates the lever 27, the upper end of which contacts with the washer 28 which is held on the stem 2 by means of the nut 20.

With the construction thus far described, it will be apparent that when the turret and with it the stem 2 is moved to the right as shown in Fig. 1, the lever 23 will throw in the clutch and thereafter the levers 25 and 27 will be actuated. The operation of the lever 27 pulls the turret to the right against the force of the spring 19 and causes the die 11 which is uppermost to come into contact with the cutting block 13 and thereby cut a lining-piece from the strip 15. The lever 25 during the first portion of its movement actuates the cementing mechanism and the strip-feeding mechanism, and during the second portion of its movement actuates the mechanism which carries the cut-out lining-piece through the receiver 9 to the heel-seat of the shoe, as will presently be described.

Turning now to the mechanism for feeding the strip of fabric and for pasting the cut-out lining piece into the shoe, the lever 25 is formed with a lug 43 and with a segmental slot 45. This lug engages a notch in the link 47, said link being pivoted to one member 49 of a clutch between which and the other toothed member 51 are arranged

spring-pressed rollers 50 which compel the member 51 to rotate with the member 49 when the latter member is rotated in a clockwise direction, but permit independent movement of the member 49 in the opposite direction. Integral with the member 49 is a plate 53 provided with a camway which is eccentric to the pin 55 upon which the member 49 and the plate 53 are rotatably mounted; and, arranged to travel in the camway, is a roller 57 which is carried at the lower end of a rod 59. A bent lever 61, fulcrumed to the frame of the machine at 63, is pivoted at one end to the rod 59 and at the other to a wide plunger 65 which normally occupies the position shown in Fig. 1. This plunger is located, as shown, in the elongated outlet of the receptacle 67 and serves, when depressed, to force a certain quantity of cement out through a plurality of small openings, one of which is shown at 68. The cement used is viscous and, on account of this quality and the small size of the openings 68, will not escape from the receptacle until the plunger is depressed. Co-operating with the toothed member or ring 51 which encircles the member 49 is a small pinion 69 which, together with a feed roll 71, is fast to a shaft 72, said shaft being mounted in suitable bearings in the frame of the machine. A second roll similarly mounted and arranged parallel to the roll 71 carries a pinion 73 which meshes with the pinion 69; and, gripped between these feed rolls, is the end of the strip 15 which is wound around a shaft 75, the ends of which are supported by yokes 77. In order to guide the strip as it is being fed forward by the feed rolls referred to above, there is provided an idle roll 79.

With the construction described above, it will be apparent that as the lever 25 is moved in a counterclockwise direction and the link 47 thereby moved to the left as viewed in Fig. 1, the effect of this movement will be to move the member 49 and the plate 53 in a clockwise direction thereby raising the rod 59 and depressing the plunger 65 so that a certain amount of cement is forced out upon the strip. At the same time the members 49 and 51 will be clutched together with the result that the pinions 69 and 73 together with their feed rolls will be rotated to pull the end of the strip a certain distance downward.

In order to determine the extent of motion transmitted to the plunger 65 as well as to the strip 15, there is provided a regulator 81 in the form of a bell crank lever which is pivoted to the frame at 83. The upright arm of this lever has fast thereto a horizontal spindle upon which is mounted a roll 85, and this roll coöperates with an inclined cam face 87 on the under side of the link 47 to raise the end of the link and

thereby disconnect it from the lug 43. The horizontal arm of the bell crank lever 81 is provided near its outer extremity with a bore to receive a locking pin 89, which is adapted to fit into any one of a plurality of holes formed in a segmental plate 91 which is fast to the frame of the machine. The point at which the link 47 and the lever 25 are disconnected can thus be varied in order to vary the extent of movement of the strip 15 as well as the amount of cement delivered to said strip.

Turning now to the mechanism for laying the pasted and died-out lining-piece in the heel-seat of the shoe, the hollow cutting block 13 has slidably mounted therein a hollow carrier or casing 93 provided with a rack 95 with which mesh the teeth of a segment gear 97 pivoted to the frame at 98, said gear being provided with a pin 99 which extends into the segmental slot 45. Slidably mounted in the hollow carrier 93 is a hollow holder 101 which carries at its outer end a smoothing or laying member, herein shown as an annular brush 103. Extending through said hollow holder is a guide rod 105 having at its left hand end as shown in Fig. 1 a presenter and spreader 107 which acts to increase the diameter of the annular brush when said brush is moved with respect to said guide and spreader in a manner which will presently be described. Fast to the right hand end of the brush holder, as shown in Fig. 1, is a pulley 109 which is continuously rotated during the rotation of the driving shaft 31 by means of a belt 111 and a pulley 113 carried by the sleeve 115, an idler pulley 117 at the end of a pivoted arm 119 serving to maintain the belt tight during the bodily movement of the small pulley 109.

Located below the arms of a U-shaped rod 121, the ends of which are held in the frame of the machine by set screws one of which is shown at 123 in Fig. 2, is a bracket 125 which is clamped to the carrier 93 by means of a screw bolt 127. This bracket is provided at its outer end with a socket and a bore leading therefrom, and the guide rod 105 is of reduced diameter at its outer end whereby there is formed a shoulder which fits against the bottom of the socket, the portion of reduced diameter being threaded as at 129 to receive a holding nut 131. A spring 133 normally under tension and tending to move the pulley 109 and with it the brush to the left is held between the end of the brush carrier 101 and the bottom of the socket in the bracket 125. This spring is maintained under tension by a latch 135 which is pivoted to the bracket 125, the upper end being engaged by a trigger 137 which is pivoted at 139 to an ear 141 on the bracket 125. This trigger has a depending forward portion which is arranged,

when the bracket together with the carrier 93 has been moved to the left by the segment gear 97, to be engaged by a stop 141, as shown in dotted lines in Fig. 1, such movement of the trigger permitting the spring 133 to become operative so that when the carrier 93 has been moved to the left to push the lining-piece into the shoe the end of the brush will be forced past the spreader 107 as shown in dotted lines in Fig. 1.

The mechanism just described has for convenience been termed the mechanism for laying the pasted lining-piece in the heel seat of a shoe. It is evident, however, that this mechanism is capable of other uses and is applicable in any case in which it is desirable to keep the brush or similar member inclosed in a casing while it is being advanced into a shoe and then to expose said brush when it reaches its operative position. It should be noted, too, that with a construction such as that described it is possible to apply to the heel-seat of a shoe a sticky object or substance without danger of smearing the lining proper of the shoe.

The operation of the machine is as follows: The spring-pin 5 is withdrawn from its socket and the turret rotated to bring the desired shoe receiver into operative position. The regulator 81 is moved to a position to cause the proper amount of material to be fed as well as the proper amount of cement to be expelled from the reservoir. A shoe is then placed upon the uppermost shoe receiver and subjected to a slight pressure. This moves the turret and with it the stem 2 a short distance to the right as shown in Fig. 1 thereby rocking the lever 23 about the stud 21 and throwing in the one revolution clutch. The effect of the first part of the rotation of the shaft 31 and sleeve 115 is to rock the lever 25 about the pivot 21 thereby moving the link 47 to the left. This causes a certain amount of cement to be delivered upon the strip 15 and at the same time pulls the strip down for a given distance and brings the cemented portion between the die 11 and the cutting block 13. The cam 41 on the sleeve 115 next comes into operative position and causes the lever 27 to pull the turret sharply to the right and thereby cut out a lining-piece from the strip 15. Just previously to this the inclined face 87 of the link 47 has ridden up on the roll 85 and disconnected the link from the lever 25. As now the lever 25 continues its movement toward the left, the right-hand wall of the segmental slot 45 contacts with the pin 99 and moves the carrier 93 together with its associated parts toward the left. The cut-out lining-piece is thus caught on the end of the presenter 107 and carried to the heel seat of the shoe. As it reaches this position the trigger 137 contacts with the stop 141 there-

by releasing the spring 133 which forces the brush out over the presenter, as shown in dotted lines, so that the lining-piece is smoothed down and properly laid in place.

5 During the remaining portion of the revolution of the shaft 31, the parts are carried back into the position shown in Fig. 1. The latch 135 contacts with the base of the U-shaped rod 121 and thereby engages the 10 trigger 137. With regard to the lug 43, it should be understood that the right-hand end wall of the notch in the lever 47 extends downwardly a sufficient distance so that the lug 43 engages this wall on its return movement.

For convenience the invention has been shown and described in connection with a machine for lining the heel seat only, but it should be understood that the particular 20 sort of sole lining handle is immaterial.

Although the invention has been set forth in connection with a particular machine it should be understood that the invention is not limited in the scope of its application to 25 the particular machine shown and described.

Having thus described my invention, what I claim as new and desire to secure by Letters Patent of the United States is:—

1. A machine for laying a lining piece in 30 the heel seat of a shoe having, in combination, a laying member, a source of supply of cement, and mechanism actuated upon presentation of the shoe in operative relation to said machine for causing cement to 35 be delivered from said supply into position to cause said lining piece to adhere to said heel seat when pressed thereagainst and the laying member to approach said heel seat.

2. A machine of the class described having, in combination, mechanism for applying a lining-piece to a shoe and automatic means for actuating said applying mechanism once for each shoe presented.

3. A machine of the class described having, in combination, mechanism for applying a lining-piece to a shoe, and automatic means arranged to become operative upon presentation of said shoe in operative relation to said machine for actuating said applying mechanism.

4. A machine of the class described having, in combination, a movable member, mechanism for applying a lining-piece to a shoe and automatic means arranged to become operative by movement of said member for actuating said applying mechanism, once for each shoe presented to be lined.

5. A machine for applying lining material to the heel seat of a shoe having, in combination, mechanism for applying cement to said material and means for operating said mechanism arranged to become operative upon presentation of said shoe in operative relation to said machine.

6. A machine of the class described having, in combination, a rotating brush, a receiver for supporting a shoe, and means responsive to pressure of said shoe upon said receiver for bringing the brush into contact with the heel-seat of said shoe.

7. A machine of the class described having, in combination, a rotating brush, a source of supply of cement, mechanism for forcing cement from said supply, mechanism for moving said brush toward the heel seat of a shoe, and a controlling member movable upon presentation of said shoe in operative relation to said machine for causing said mechanisms to perform their operations.

8. A machine of the class described comprising a hollow casing, a brush normally wholly within said casing, means for rotating said brush, and means responsive to presentation of a shoe in operative relation to the machine for causing relative movement between said brush and casing to expose said brush.

9. In a machine for pasting a heel seat lining to the heel seat of a shoe, means for applying cement to one of said parts comprising a hollow casing and a rotary brush normally inclosed therein, said brush being movable axially relative to said casing upon presentation of said shoe, in operative relation to said machine.

10. A machine of the class described having, in combination, a hollow receiver to which a shoe is adapted to be presented, an applying member movable through said receiver, and means responsive to pressure of said shoe upon said receiver for causing said member to apply a sticky substance to the heel seat of said shoe.

11. A machine for laying heel seat linings in shoes having, in combination, a hollow receiver upon which the shoe is placed, an applying member for forcing a lining piece through said receiver to the heel seat of said shoe, and means for delivering a lining piece between said member and heel seat preparatory to the laying operation.

12. A machine of the class described having, in combination, mechanism for cutting from suitable material a lining-piece for a shoe and automatic means arranged to become operative upon presentation of said shoe in operative relation to said machine for actuating said mechanism.

13. A machine of the class described having, in combination, mechanism for applying a lining-piece to a shoe, mechanism for feeding a lining-piece to said applying mechanism and means for actuating said mechanisms.

14. A machine of the class described having, in combination, mechanism for applying a lining-piece to a shoe, mechanism for

- feeding a lining-piece to said applying mechanism and automatic means for actuating said mechanisms. 23. A machine for applying lining material to the heel seat of a shoe having, in combination, a movable member, mechanism for applying cement to said material, mechanism for applying the cemented material to said heel seat, and means arranged to become operative by movement of said member for operating said mechanisms successively. 65
15. A machine of the class described having, in combination, mechanism for applying a lining-piece to a shoe, mechanism for feeding a lining-piece to said applying mechanism and automatic means arranged to become operative upon presentation of said shoe in operative relation to said machine for actuating said mechanisms. 10 70
16. A machine of the class described having, in combination, mechanism for cutting a lining-piece from suitable stock, mechanism for applying said lining-piece to a shoe, and means for actuating said mechanisms successively. 24. A machine of the class described having, in combination, a receiver for a shoe, mechanism for applying a lining piece to said shoe, and automatic means arranged to become operative by pressure of said shoe against said receiver for actuating said applying mechanism. 75
- 15 80
17. A machine of the class described having, in combination, mechanism for cutting a lining-piece from suitable stock, mechanism for applying said lining-piece to a shoe, and automatic means for actuating said mechanisms successively. 25. A machine for applying lining material to the heel seat of a shoe having, in combination, a receiver for said shoe, mechanism for applying cement to said lining material, mechanism for applying the cemented material to the heel seat of a shoe, and automatic means arranged to become operative by pressure of said shoe against said receiver for operating said mechanisms 85
- 20 90
18. A machine of the class described having, in combination, mechanism for cutting a lining-piece from suitable stock, mechanism for applying said lining-piece to a shoe, and automatic means arranged to become operative upon presentation of said shoe in operative relation to said machine for actuating said mechanisms successively. 26. A machine of the class described, having, in combination, mechanism for cutting out a lining piece from suitable material, mechanism for laying said piece in a shoe, and cement applying mechanism arranged to be operated to apply cement to the material of said piece prior to the operation of said laying mechanism. 95
- 25 100
19. A machine of the class described having, in combination, a movable member, mechanism for cutting a lining-piece from suitable stock, mechanism for applying said lining-piece to a shoe, and automatic means arranged to become operative by movement of said member for actuating said mechanisms successively. 27. A machine of the class described, having, in combination, mechanism for cutting out a lining piece from suitable material, mechanism for laying said piece in a shoe, cement applying mechanism arranged to be operated to apply cement to the material of said piece prior to the operation of said laying mechanism, and automatic means for actuating said mechanisms. 105
- 30 110
- 40 20. A machine of the class described, having, in combination, a support over the end of which a shoe may be positioned to receive lining material fed relatively to said support into position to contact with the inside of the bottom of a shoe placed on said support, and means for coating said material with an adhesive substance prior to its application to the inside of said shoe. 28. A machine of the class described, having, in combination, mechanism for cutting out a lining piece from suitable material, mechanism for laying said piece in a shoe, cement applying mechanism arranged to be operated to apply cement to the material of said piece prior to the operation of said laying mechanism, and automatic means arranged to become operative upon presentation of a shoe in operative relation to said machine for actuating said mechanisms. 115
- 45 120
- 50 21. A machine for applying lining material to the heel seat of a shoe having, in combination, mechanism for applying cement to said material, mechanism for applying the cemented material to said heel seat, and automatic means for operating said mechanisms successively. 29. A machine of the class described, having, in combination, mechanism for cutting out a lining piece from suitable material, mechanism for laying said piece in a shoe, cement applying mechanism arranged to be operated to apply cement to the material of said piece prior to the operation of said laying mechanism, and automatic means arranged to become operative by contact with a shoe. 125

30. A machine of the class described having, in combination, a receiver for a shoe, mechanism for cutting a lining piece from suitable stock, mechanism for applying said lining piece to the shoe, and automatic means arranged to become operative by pressure of said shoe against said receiver for actuating said mechanism successively.

31. A machine of the class described having, in combination, a device for applying a lining-piece to a shoe, a hollow member for receiving the shoe during the application of said piece, and automatic means arranged to become operative upon pressure of said shoe against said shoe-receiving member for actuating said applying device.

32. A machine of the class described having, in combination, a support for a shoe, mechanism for applying a lining piece to the shoe so supported, and mechanism for feeding lining pieces successively to said applying mechanism.

33. A machine of the class described having, in combination, a device for applying a lining-piece to a shoe, a hollow member for receiving the shoe during the application of said piece, and automatic means arranged to become operative upon presentation of said shoe in operative relation to said machine for causing said applying device to force the lining-piece along the receiving member to the heel-seat of the shoe.

34. A machine of the class described having, in combination, a rotating brush for laying a lining-piece in a shoe, a member for receiving the shoe during the laying of said piece, and means for causing said brush to approach said shoe.

35. A machine of the class described having, in combination, a rotating brush for laying a lining-piece in a shoe, a member for receiving the shoe during the laying of said piece, and automatic means arranged to become operative upon presentation of the shoe in operative relation to said machine for causing said brush to approach said shoe.

36. A machine of the class described having, in combination, a member for presenting a lining-piece to a shoe, a member for receiving said shoe during the presentation of said piece, a brush adapted to coöperate with said presenter in applying said piece, said brush being normally retracted with respect to said presenter, and means for first moving the presenter and brush in unison toward the shoe and then moving the brush past the end of the presenter.

37. A machine of the class described having, in combination, a member for presenting a lining-piece to a shoe, a member for receiving said shoe during the presentation of said piece, a brush adapted to coöperate with said presenter in applying said piece, said brush being normally retracted with respect to said presenter, and automatic

means becoming operative upon presentation of said shoe in operative relation to said machine for first moving the presenter and brush in unison toward the shoe and then moving the brush past the end of the 70 presenter.

38. A machine of the class described having, in combination, a device for applying a lining-piece to a shoe, a member with respect to which said device is movable, a member 75 for receiving the shoe, one of said members being provided with a cutting die and the other with a cutting bed, and means for causing relative movement between said die and bed and for actuating said applying 80 device.

39. A machine of the class described having, in combination, a device for applying a lining-piece to a shoe, a member with respect to which said device is movable, a member 85 for receiving the shoe, one of said members being provided with a cutting die and the other with a cutting bed, and automatic means for causing relative movement between said die and bed and for actuating 90 said applying device.

40. A machine of the class described having, in combination, a device for applying a lining-piece to a shoe, a member with respect to which said device is movable, a 95 member for receiving the shoe, one of said members being provided with a cutting die and the other with a cutting bed, and automatic means arranged to become operative upon presentation of a shoe in operative relation to said machine for causing relative movement between said die and bed and for actuating 100 said applying device.

41. A machine of the class described having, in combination, mechanism for feeding 105 successive portions of a strip of material into position to be operated upon, mechanism for cutting from said strip a lining-piece for a shoe, mechanism for applying said piece to said shoe, and means for actuating said 110 mechanisms successively.

42. A machine of the class described having, in combination, mechanism for feeding successive portions of a strip of material into position to be operated upon, mechanism for cutting from said strip a lining-piece for a shoe, mechanism for applying said piece to said shoe, and automatic means 115 for actuating said mechanisms successively.

43. A machine of the class described having, in combination, mechanism for feeding successive portions of a strip of material into position to be operated upon, mechanism for cutting from said strip a lining-piece for a shoe, mechanism for applying 125 said piece to said shoe, and automatic means arranged to become operative upon presentation of said shoe in operative relation to said machine for actuating said mechanisms successively.

44. A machine of the class described having, in combination, mechanism for applying cement to a strip of material, mechanism for feeding said strip, mechanism for cutting from said strip a lining-piece for a shoe and automatic means arranged to become operative upon presentation of said shoe in operative relation to said machine for actuating said mechanisms. 5
45. A machine of the class described having, in combination, a receptacle for cement, said receptacle being provided with an outlet, a plunger for forcing cement from said outlet upon a strip of material, feeding mechanism for advancing said strip, mechanism for cutting from said strip a lining-piece for a shoe, and means for actuating said plunger, feeding mechanism and cutting mechanism. 10
46. A machine of the class described having, in combination, a receptacle for cement, said receptacle being provided with an outlet, a plunger for forcing cement from said outlet upon a strip of material, feeding mechanism for advancing said strip, mechanism for cutting from said strip a lining-piece for a shoe, and automatic means arranged to become operative upon presentation of said shoe in operative relation to said machine for actuating said plunger, feeding mechanism and cutting mechanism. 15
47. A machine of the class described having, in combination, means for applying a lining-piece to a shoe, a plurality of shoe receiving members, and means for maintaining a selected member in operative relation to the applying means. 20
48. A machine of the class described having, in combination, a device for applying a lining-piece to a shoe, means for actuating said device, a hollow member through which said device is moved during its actuation, said member being provided with a cutting bed, a plurality of shoe-receiving members provided with cutting dies and means for maintaining a selected receiving member in operative relation to said cutting bed and applying device. 25
49. A machine of the class described having, in combination, mechanism for applying cement to a piece of material, mechanism for applying the cemented material to the heel seat of a shoe, and automatic means for operating said mechanisms. 30
50. A machine of the class described having, in combination, mechanism for applying cement to a piece of material, mechanism for applying the cemented material to the heel seat of a shoe, and automatic means arranged to become operative upon presentation of the heel seat of a shoe in operative relation to said machine for operating said mechanisms. 35
51. A machine of the class described having, in combination, mechanism for applying cement to a piece of material, mechanism for applying the cemented material to the heel seat of a shoe, and means for operating said mechanisms. 40
52. A machine of the class described, having, in combination, a support over which shoes may be positioned for receiving a sole lining, means for feeding linings relatively to said support in such manner that each lining is moved into position to contact with the inside of the bottom of a shoe, and means for applying an adhesive substance to the material of said sole linings. 45
53. A machine of the class described, having, in combination, a support over which shoes may be positioned to receive sole linings, and means for automatically feeding sole linings relatively to said support in such manner that each lining is brought into position to contact with the inside of the bottom of the shoe. 50
54. A machine of the class described, having, in combination, a support over the end of which shoes may be positioned for receiving linings, means for feeding linings relatively to said support into position to be applied to the inside of the bottoms of said shoes, and means for applying an adhesive substance to the material of said linings prior to the application of said linings to said shoes. 55
55. A machine of the class described, having, in combination, mechanism for applying a lining piece to a shoe and mechanism for coating the material of said piece with an adhesive substance prior to the applying operation. 60
56. A machine of the class described, having, in combination, mechanism for applying cement to the material of a lining piece, mechanism for applying said lining piece to a shoe, and means for actuating said mechanisms. 65
57. A machine of the class described, having, in combination, mechanism for applying cement to the material of a lining piece, mechanism for applying said lining piece to a shoe, and means arranged to become operative upon presentation of a shoe in operative relation to said machine for actuating said mechanism successively. 70
58. A machine for applying sole linings to shoes having, in combination, a holder for the lining material, means for moving said material from said holder into position to permit the operator to present the shoe in position to receive said material, and means for applying cement to said material during said movement. 75
59. A machine for applying lining material to shoes, having, in combination, a holder for said material, means for moving said material into position to be applied to the inside of a shoe, and means for applying cement to said material. 80

60. In a machine of the class described, the combination of a support over which shoes are adapted to be positioned for receiving a sole lining, and means for automatically feeding sole linings relatively to said support in such manner that each lining is positioned for contact with a face of a shoe sole.

In testimony whereof I have signed my name to this specification in the presence of 10 two subscribing witnesses.

FREDERICK M. FURBER.
